UNITED STATES PATENT OFFICE

CHARLES R. BEDDOW, OF MIAMI, FLORIDA, ASSIGNOR TO SIMPLEX MANUFACTURING COMPANY, OF MIAMI, FLORIDA, A CORPORATION OF FLORIDA

SELF-WRINGER MOP

Application filed October 24, 1929. Serial No. 402,242.

The present invention relates to mops and more particularly to self-wringing mops.

An object of this invention is to provide a device of this character having wringing means associated with the mop whereby the mop may be twisted or wrung without touching the wet cloth or other material secured to the head of the mop.

Another object of this invention is to provide a device of this character wherein the mopping material may be securely locked in position on the head of the device and the wringing means locked in position so as not to interfere with the normal use of the mop.

15 The above and various other objects and advantages of this invention will in part be described in and in part be understood from the following detailed description of the present preferred embodiment, the same being illustrated in the accompanying drawings wherein:—

Fig. 1 is a top plan view of a device constructed according to my invention;

25 Fig. 2 is a side elevation showing the wringer in position for operation;

Fig. 3 is a top plan view showing the wringer in locked position;

Fig. 4 is a side elevation of the device;

20 Fig. 5 is a transverse section on the lines 5—5 of Fig. 4;

Fig. 6 is a transverse section taken on the lines 6—6 of Fig. 4, and

Fig. 7 is a transverse section taken on the lines 7—7 of Fig. 3.

35 Referring to the drawings the numeral 10 designates a handle of a mop which may be of any desired length and is preferably circular in cross section. The handle 10 is adapted to be provided at its lower end with a body portion 11 which may be mounted on the handle in any suitable manner. The body portion 11 is preferably constructed of metal and substantially surrounds the periphery of the handle and is provided with an outer portion 12 which is preferably flat, the purpose of which will be more fully understood from the details of construction hereinafter described.

40 The lower end of the body portion 11 is preferably angularly inclined and it is pro-

vided with a reduced end portion 13, the opposite sides of which are formed to engage the opposite arms 14 of a substantially T-shaped mop head 15. The upper ends of the arms 14 are preferably angularly inclined as at 14^a and the body portion 11 is adapted to securely hold the arms in position thereon.

The body 11 is provided with a longitudinally slotted portion 16 spaced inwardly from the opposite ends thereof, and the lower end of the body 11 is preferably arcuately inclined as at 17, the purpose of which will be described later.

The mop head 15 is provided with a slidably engaging member 18 of substantially T shape, the reduced portion of which is arcuately inclined as at 19 so as to engage the outer side portions of the arms 14. A pair of outstanding lugs 20 are mounted on the arms 14 spaced upwardly from the lower end thereof. The lugs 20 provide stopping means for holding the engaging member 18 in adjusted position.

The lower edge portion of the engaging member 18 is provided with a toothed head 21 which is adapted to securely hold a mop rag or the like on the lower portion of the mop head. The mop head 15 is preferably angularly inclined from the arms 14 so as to permit the securing member 18 to move outwardly and substantially between the spaced T members 22 of the head.

A wringing member generally designated as 23 is adapted to loosely engage in the slot 16 of the body 11 and is provided with a pair of substantially T-shaped members at the opposite ends thereof. The lower end of the wringer member 23 is looped so as to provide a substantially T-shaped loop at the lower end of the wringer, one end of the loop being open as at 24 and spaced outwardly from the body of the wringer so as to permit insertion of the mop rag or the like thereon.

The upper end of the wringer 23 is provided with a substantially T-shaped handle member 25. The handle member 25 may be formed of the same material as the body of the wringer by being bent into the form of a loop, the open end being bent downwardly

in substantially parallel relation to the body 23 of the wringer and in spaced relation thereto so as to provide a locking member 26 for holding the wringer on the handle.

5 A hook member 27 is mounted on the upper rounded portion of the body 11 and is adapted to hold the body 23 of the wringer on the handle. Spaced downwardly from the handle 25 the body 23 is provided with 10 an outstanding portion 28 which lies in substantially the same plane as the handle 25 so that when the body 23 engages the hook 27 the outstanding portion 28 will lie against the outer face of the body 11 and coacting 15 with locking member 26 will prevent turning movement of the handle 23.

The body portion 11 at the lower end thereof is provided with a pair of depending lugs 29 which are adapted to engage the wringer 23 so as to prevent lateral movement thereof. 20 In use, when it is desired to place a mop rag or the like on the mop head 22 the resilient arm members 14 of the mop head may be pinched together by the hand so as to permit the securing member 18 to be moved upwardly on the arms.

The mop rag may be looped over the head portion 30 of the wringer and the open ends brought downwardly so as to engage the 30 head portion 22 of the mop head. The securing member 18 may then be positioned downwardly over the stop members 20 until the toothed portion 21 of the securing member engages the open ends of the mop rag securely positioning the mop rag on the mop head.

When in inoperative position the wringer member 23 lies substantially in parallel relation to the arms 14 and in the same plane 40 as the upper edge portion of the body 11. The hook or wringer securing member 27 is adapted to engage the wringer 23 and when the wringer has been positioned downwardly into inoperative position the spring 45 portion 26 of the handle will prevent lateral movement thereof with respect to the body 11 coacting with the depending lugs 29.

The outstanding portion 28 of the wringer 23 coacting with the securing member 26 50 of the handle prevents turning movement of the wringer on the body 11. When it is desired to use the wringer the handle portion 25 is grasped and pulled upwardly until the 55 spring or holding member 26 passes the hook member 27 and the offset portion 28 is opposite the hook 27 whereupon the wringer may be swung outwardly of the body 11 and the mop rag may be coiled in the usual manner so as to wring the water therefrom.

60 It is, of course, understood that any type of mop rag may be used with this device and that various changes and modifications may be made in the details of construction and design of the above specifically described

embodiment of the invention without departing from the spirit thereof, such changes and modifications being restricted only by the scope of the following claims.

What is claimed is:—

70 1. In combination, a mop comprising a body portion having a substantially flat outer face, means for removably securing a mop rag to said body, said body having an elongated slot therethrough, a wringer loosely mounted on the body and extending through the slotted portion thereof, mop rag engaging means on said wringer at the lower end thereof, handle means mounted on the upper end of said wringer, a hook mounted on the outer face of said body and adapted to engage the body of the wringer, and securing means carried by the wringer and engaging said hook for holding the wringer on the body against turning movement said securing 85 means being adapted to release the wringer upon longitudinal movement thereof on the body.

90 2. In combination, a mop comprising a body member, a pair of spaced resilient arm members secured to said body member, a mop head mounted on said arms, a slideable toothed securing member engaging said arms and adapted to hold a mop rag on the head, stop means on said arms for holding the securing member in adjusted position, said body member having an elongated slot therethrough, a wringer member engaging the mop rag and adapted to loosely engage said body through the slot, a hook mounted on the body member and adapted to engage said wringer for holding the wringer in inoperative position, and securing means carried by the wringer for holding the wringer in engagement with said hook whereby to prevent lateral movement of the wringer with respect to the body, said wringer being adapted to be released from the hook upon longitudinal movement thereof on the body.

3. In combination, a mop comprising a body having a flat face, a pair of resilient arms mounted on the body and extending downwardly therefrom and in substantially parallel relation to each other, a mop head mounted on said arms, means for removably securing one end of a mop rag to said mop head and a wringer secured to the other end of the mop rag, said wringer comprising a body portion, means for engaging the mop rag, an upstanding securing member on said mop body, a looped handle for said wringer, said looped handle having a resilient locking member secured thereto and extending in substantially parallel relation with said body of the wringer and adapted for engagement with said securing member for holding the wringer against rotation, said wringer having a portion offset from the body thereof oppositely from said locking member and co-

operating therewith whereby to hold said wringer against turning movement on the handle, said wringer being adapted to be released from the mop body upon longitudinal movement on the mop body.

4. In combination, a mop comprising a body, a mop head mounted on the body, means for removably securing a mop rag on the head, said body having a slot there-through spaced inwardly from the opposite ends thereof, a wringer adapted to engage said body through the slotted portion thereof, mop rag securing means on the wringer, a handle for said wringer, means for securing the wringer handle on the body of the mop and means cooperating with said securing means for holding the wringer handle on the body of the mop against turning movement, said wringer holding means being adapted to release the wringer upon longitudinal movement thereof on the mop body.

In testimony whereof I hereunto affix my signature.

CHARLES R. BEDDOW.
